UNITED STATES PATENT OFFICE.

GEORGE H. FOWLER, OF TAUGHANNOCK FALLS, NEW YORK, ASSIGNOR TO
FLORA FOWLER, OF SAME PLACE.

HARVESTER-KNIFE GRINDER.

SPECIFICATION forming part of Letters Patent No. 534,470, dated February 19, 1895.

Application filed May 14, 1894. Serial No. 511,083. (No model.)

To all whom it may concern:

Be it known that I, GEORGE H. FOWLER, of Taughannock Falls, in the county of Tompkins, in the State of New York, have invented 5
new and useful Improvements in Harvester-Knife Grinders, of which the following, taken in connection with the accompanying drawings, is a full, clear, and exact description.

My invention relates to harvester knife 10 grinders.

My object is to produce a sharpener for the knives of harvesters in which the knife bar and knives thereon are secured in a sliding frame; in which a rotating emery, or other 15 grinding wheel, is mounted upon a frame which is adjustable to vary the pitch or inclination of the wheel by means of a ball and socket joint which supports the wheel frame, means being provided whereby said grinding 20 wheel is very rapidly rotated; said wheel being adjustable to fit the bevel-faces of the knives; and in which the knife-bar frame is pivoted upon the guide rod which it traverses.

My invention consists in the several novel 25 features of construction and operation hereinafter described and which are specifically set forth in the claim hereunto annexed. It is constructed as follows, reference being had to the accompanying drawings, in which—

Figure 1, is a front elevation of the apparatus as in use. Fig. 2, is a top plan thereof the dotted lines indicating the varying lateral adjustment of the grinder to fit the different bevels of the knife. Fig. 3, is an end 35 elevation of the same, the dotted lines indicating the forward and back adjustment of the grinder, and further showing the knife-frame tilted over back. Fig. 4, is a transverse vertical section of the knife frame. Fig. 40 5, shows a side elevation and a top plan of one member of the hinge which carries the knife-frame. Fig. 6, is a front elevation and a side elevation of the other member of said hinge. Fig. 7, is a front elevation and side 45 elevation of the grip-bar. Fig. 8, is a plan of the rod which constitutes the hinge-pintle and also the rail upon which the knife-frame traverses. Fig. 9, is a side elevation of the frame which carries the grinder, the wheel 50 and driving gearing being shown in dotted lines. Fig. 10, is a vertical section of the same. Fig. 11, is a section of the same on

line —x—, —x—, in Fig. 9. Fig. 12, shows three views of one-half of the case of the ball and socket joint. Fig. 13, is an elevation of 55 the other member of said joint.

—A— is the base of the machine, upon which the hinge sections —2— are adjustably secured by means of bolts through the slot —3— in each; and —4—, —4—, are the 60 other hinge sections, while —5— is the pintle rod which connects said sections and completes the hinges which are located any desired distance apart.

The sections —4— are each provided with 65 a longitudinal rib —6—, and these sections are adapted to traverse said rod. A bar —7— is secured on one side of these sections by suitable bolts, and —8— are clips upon the front of these sections, held straight by said 70 rib, and constituting one of the jaws to hold the knife bar —9— upon which the knives, or cutters —10—, are secured, the whole creating the cutter-bar holder mounted upon said rod as a track.

—B— is a frame, comprising a body, a horizontal tubular bearing —11—, at the top, an arbor —12— at the lower end, and a ball —13— integral with each other, said ball fitting into a sectional socket —14— and —15— 80 is a bolt passed through said socket sections and said ball, and one of said sections is provided with a shank —16— which, as a pivot, fits into a hole in the base —A—. In the bearing —11— a shaft is journaled having 85 on one end a pinion —17— and upon the other the grinding cutter —18— as an emery wheel, and —19— is a drive gear journaled upon the arbor —12— and provided with a handle —20— mounted in one of the spokes. 90

It will be seen that the grinding frame can be swung laterally as shown in Fig. 2, by the full and dotted lines to grind the bevels of the knives; that it can be swung out of a vertical in order that the grinder may sharpen 95 the knives down to the heel of each cutting edge; that the cutter-barholder can be swung over toward and against the grinder to facilitate the grinding; and that the combined swinging of the cutter-bar holder, and the 100 mounting of the grinding frame and wheel upon a universal joint produces a machine adapted to grind the knives in any manner desired.

What I claim as my invention, and desire to secure by Letters Patent, is—

In a harvester grinder, a base or support upon which the frame is pivoted; the frame provided with a tubular bearing at its upper end, the arbor for the driving wheel at its lower end, and the perforated bearing; the driving wheel mounted on the arbor; and the shaft, provided with a pinion at one end, and the emery wheel at the other; combined with the sectional socket, which is applied to opposite sides of the perforated part of the frame, and provided with a pivotal bolt which

passes down through the support, and upon which bolt the frame has a partially turning movement; and means for reciprocating the blade back and forth in front of the emery wheel; the sectional socket serving to allow the angle of the frame to be changed at will, substantially as shown. 20

In witness whereof I have hereunto set my hand this 16th day of April, 1894.

GEO. H. FOWLER.

In presence of—

M. M. BORST,

HOWARD P. DENISON.
